UNITED STATES PATENT OFFICE.

LYLE JOHN CAMERON, OF BLUNDELLSANDS, NEAR LIVERPOOL, ENGLAND.

HARVESTING MACHINE.

Application filed January 16, 1922, Serial No. 529,778, and in Great Britain January 20, 1921.

This invention relates to harvesting machines of the kind in which mechanism is provided whereby groups of sheaves of grain or the like, after being formed in the semblance of shocks or stooks, are deposited on the ground in an upright position; and my invention is essentially characterized by the use or provision, as the means for conveying the groups of sheaves, of a ring, or ring like structure, formed in two or more parts, and means whereby the component parts of said ring may be closed and opened and advanced and retracted in such manner that it (the ring) will grip and hold a group of sheaves after being formed in the semblance of a shock of stock near the tops thereof, carry same to the desired point of discharge or delivery, deposit it as a shock or stock upon the ground, and then open to release it so that it will stand firmly and in a stable condition on the ground.

Said ring may be constructed in various ways, as for instance, it may be composed of two substantially semi-circular components each of which in turn may be built up of a number of hinged or pivoted segments; and the actuation of the ring may be effected in any convenient manner, but I prefer that said ring with its carriers, et cetera, shall be mounted upon a suitable platform, frame, or the like, which is so controlled that at the time of the deposit of a shock or stock upon the ground said frame is travelling rearwardly at or about the same speed as the machine is travelling forwardly, so that the shock or stock is deposited upon the ground as if from a stationary machine or carrier.

If necessary or desirable in order to ensure the stationary deposit of a shock or stock upon the ground, it may be arranged that the holding ring shall remain at rest for a period which will enable it to open and clear itself of the shock or stock before being moved forwardly again to receive a further supply.

Said ring components may be of any suitable shape or configuration, so that when the parts are assembled the ring may be round, rectangular, or elliptical; and the interior faces thereof may be roughened, toothed, serrated, or provided with prongs, in order to enhance their gripping effect upon the shock or stock.

I will further describe my invention with

the aid of the accompanying sheets of diagrammatic drawings, which illustrate, by way of example only, one mode whereby the same may be carried into effect.

In said drawings:

Fig. 1 is a longitudinal section of the apparatus and

Fig. 2 is a plan.

Fig. 3 is a transverse section taken on line 3—3 Fig. 1 but showing the stooking ring closed.

Fig. 4 is a transverse section taken on line 4—4 showing the binder.

Fig. 5 is an enlarged detail of a portion of the apparatus.

The apparatus as shown, is an attachment or adjunct to a binder or self-binder reaper.

There is provided a steel main frame X, rectangular in shape, which frame is carried at its outer side on a pair of wheels, and its inner side is supported by the frame of the binder and wheels, if necessary; power may be transmitted to it for the operation of its parts from the binder. This main frame carries and supports (a) a receptacle 39 and 37 for receiving the sheaves from the binder; (b) a stock-forming or moulding mechanism 30 and 32 whereto the sheaves are carried from the receiver 39 and 37 and arranged in the form of a stock (which preferably comprises six sheaves of grain) in a horizontal position, and held until grasped by the stooking ring, and (c), a stooking ring.

As the binder and stooking machine are moving forward, say at the rate of three and a half to four miles per hour, the stooking ring must move backward at the same speed so that the stock may be deposited on the ground as if from a stationary machine. To effect this operation mechanism is provided in the form of a gliding frame 3, 13, 15, which operates inside said main frame. This gliding frame consists of two chief parts:

(1) An upper part consisting of a horizontal bar 3 rigidly attached to two longitudinal bars 15 which ride on two wheels 18 each on the upper part of the main frame 21, 22, and which gliding frame moves directly backward and forward within a range of say eight feet (power being transmitted to it and its movements timed by suitable mechanism located in the main frame) and

two vertical pillars or pivots 13 passing through the horizontal bar 3 and adapted to control the respective halves of the stooking ring 1.

5 (2) The stooking ring 1 and the mechanism 9, 2, which carries and controls each ring component.

Said main frame should admit of being raised and lowered in relation to the ground 10 according as the grain to be cut is long or short, and it, of course, must be open below at the rear end to permit of the stook to pass out.

Fig. 1 of the drawings shows an upper 15 track 21 and 22 which carries the upper part of the gliding frame, and a lower track 19 and 20 which carries supports 9 et cetera of the stooking ring by means of a flange wheel 17. Said lower track has, (a) a horizontal

20 part which carries the stooking ring directly backward until the stook has been pulled clear of the moulding or stook-forming cones 30, 32, and has swung downward in a vertical position; and (b), a sloping or inclined part which permits the stooking ring and stook to drop directly to the ground, and at the same time to be carried backward at the same speed as the whole machine travels forward, so that the stook when 25 dropped will be practically standing still as regards horizontal motion in relation to the ground.

The lower track is jointed at 23 immediately in front of the bend, and the rear 30 end is so arranged that the rear part of the track 19, 20 may move up and down from the joint 23 and gap 24, to permit of variations in lengths of sheaves.

Fig. 3 of the drawing illustrates the gliding frame 3, 13, and 15, showing the stooking ring 1 in a vertical position and closed, as it will be when it has grasped the stook and is withdrawing it from the stook-forming cones 30, 32.

45 It also shows a cross section of vertical pivots 13 which are located in a boxing 9 below the level of the cross bar 3 of gliding frame 3, 13, 15.

Fig. 2 of the drawing shows in plan the 50 gliding frame, 3, 13, 15 and vertical pivots 13 in full lines and moving forwardly to receive a stook and in dotted lines, depositing a stook upon the ground, and showing the structure of the frame and its carrying wheels 18, and the top view of the vertical pivots 13 which are part of the gliding frame 3, 13, 55 15 and are at this part round so that they can rotate each around its vertical axis.

The rotation of each pivot 13 is co-ordinated in relation to the other by means of a lever 5 which, in turn, is attached to the lever 5 of the pivot 13 on the opposite side by means of a cross bar 12.

60 Referring again to Figs. 1 to 4:—

65 The stooking ring 1 is provided with

prongs 27^a more or less radially arranged; said stooking ring is made up of two separate and distinct halves, each of which consists of a central part 26 whereto is solidly attached the horizontal pivot 2 and terminal segments 27 at each end of the central part 26, such segments being suitably pivoted to open and close in the plane of the stooking ring and controlled by rods 10 working on a lever 28 on each segment. As each half of the stooking ring swings forward or backward (see Figs. 1 and 2) through the rotation of the vertical pivots 13 they separate, and also each distal segment 27 is pulled open by the rods 10 acting on the segment levers 28, and the stooking ring is thus opened, either to grasp or release its load—the stook of sheaves.

Said horizontal pivots 2 are carried in the stooking carriers 9, one on each side; they are permitted to rotate only through an angle of 90°. Rotation through this angle is necessary as the stooking ring must be in the vertical plane when grasping its load and in a horizontal plane when releasing it. The rotation of the stooking ring, from its normally vertical position to a horizontal position, is effected by the stook but it (the ring) returns to its original position due to one side of said ring being heavier than the other.

3 is a heavy cross bar designed to maintain the rigidity of the gliding frame 3, 13, 15; it is attached to the longitudinal bar 15, and passing through it are the vertical pivots 13.

6 is a ring which passes around each stooking ring carrier 9 and has attached to it the wheel 17, which carries said stooking ring carrier 9, stooking ring 1 and its load of sheaves. A stooking ring carrier 9 may rotate inside its ring 6 so that the wheel 17 remains in a straight line on its track.

16 is a control rod the downturned outer end whereof rides in an appropriately curved groove 16^a formed in a guide plate 16^b secured to ring 6; the ends of said guide plate 16^b abut against the adjacent vertical bars 14 and are free to slide up and down on said bars; thus the guide plate is prevented from turning. The inner end of said rod 16 is grooved to fit over a ridge running around the control cuff 8 and pulls said cuff outward and through it the control rods 10 outward, to open the distal segments 27 when the stooking ring 1 swings backward or forward to open. As the stooking ring swings to the centre, the reverse action takes place.

Said control cuff 8 encircles its horizontal pivot 2 and is free to slide longitudinally on same, but cannot rotate around it. It is controlled by a pin on the pivot 2 sliding in the groove in the cuff 8. To said cuff are attached the control rods 10, so that as said

cuff 8 is moved inwards or outwards by the control rods 16 the distal segments 27 will be closed or opened.

A stooking ring carrier 9 possesses two chief parts:—(a) a vertical part square inside where it surrounds the square vertical pivots 13; this carrier 9 is a smooth bore boxing free to slide up and down on the pivot 13, but is controlled in its rotation, however, by said pivot 13; it is free to rotate inside the ring 6 which carries it and regulates its height, the ring 6 being carried by the wheels 17; and (b) a horizontal part carrying the horizontal pivot 2 of its stooking ring; this must allow the horizontal pivot 2 to rotate on its long axis through an angle of 90°. As it is essential that the vertical part of the carrier 9 shall slide easily up and down on the pivot 13, and as it will tend to be twisted out of the line of the pivot 13 by the weight of the load in the stooking ring 1, it may be necessary to provide small wheels or rollers at the upper and lower ends of this vertical part to run on the pivot 13 to prevent binding or gripping.

Said vertical pivots 13 control the opening and closing of the stooking ring 1 and also carry it backward and forward at the same time allowing it to fall and rise according to the bend of the lower track 19 and 20. At their upper ends they pass through the bar 3 of the gliding frame 3, 13, 15, the passages whereof are round so that the pivots 13 may rotate on their long axes.

There are provided upright bars 14 which are parallel with the vertical pivots 13—a pair on each side; these are attached above to the longitudinal bars 15, and may be connected together at their lower ends; they prevent the guide plate 16^b from turning and add rigidity to the vertical pivot 13.

Said control rod 16 lies in a groove or slot on the horizontal part of the stooking ring carrier 9 and pulls the cuff 8 to open the distal segments 27.

The members 19 and 20 of the lower track are suitably attached together so as not to interfere with the passage of the wheels. Tracks 21 and 22 are similar to tracks 19 and 20, but these are not jointed or broken, and run straight from front end to rear.

Figs. 1 and 2 show the approximate positions and relationship of the binder or self-binding reaper and stooking apparatus: They also show the stooking ring 1 open and moving forward to grasp the load of sheaves or stook, and stooking ring closers.

Each stooking-ring closer comprises an arm 25^a attached to the horizontal pivot 2, and a flat piece of wood 25^b. As the stooking ring 1 is carried forward, open as shown, the flat pieces 25^b abut against the top of the stook held in the moulder 30, 31, 32, and close the two halves of the ring 1.

Fig. 2 shows a plan view of the sheaf

holder comprising a series of rods 39; this holds the sheaves as they are dumped from a binder of any known kind. The sheaves cannot be carried into the stook moulder 30, 31, 32, all the time as fast as they are thrown from the binder, because the stook moulder 42 must stop running while the stooking ring 1 is grasping its load.

Fig. 4 shows how the stook moulder is divided into six spaces by the sheaf spacer plates 31; it also shows the sheaf holder 39, one (33^a) of two sheaf carriers 33^a, 33^b, and the top of sheaf holder 37, loader 42, and sheaf arrester 38. Said sheaf holder top 37 comprises a series of rods similar to 39 and prevents upward and tilting displacement of the sheaves whilst being carried on to the loader 42 and permits of only one sheaf at a time to be carried to the moulder. Said rods also project upward towards the moulder 30, 31, 32, hold the sheaves in place, and direct them into the moulder.

Fig. 4 also illustrates how the sheaves are thrown into the holder 39 and carried by the carriers (33^a and 33^b) on to loader 42, and by loader 42 into the moulder 30, 31, 32.

30 is the inside cone (truncated). It may be of sheet metal on a frame, or rods on a frame; it is mounted on the shaft 41 around which it can rotate, and which shaft is supported in the wall 40 and at the front of the machine. Said cone 30 is provided with six spacer plates or spokes 31 which divide its sloping surface into six areas, one for each sheaf. In these areas the sheaves are held in proper arrangement and are so spaced as to form a well shaped stook or shock. The sheaves are carried into these spacers, one at a time, by the loader 42. Each sheaf is caught by the fin or arm 43 on the loader, and directed by the rods of sheaf holder 39 underneath and the top rods 37 above into the moulder 30, 31, 32. The sheaf comes against the spacer rod 31, causes the inside cone 30 to revolve, and passes under the outside cone rods 32, moving up the parts 32^a which are hinged at 44. As soon as the loader fin 43 ceases to press on the sheaf, the inner cone 30 ceases to revolve and will remain stationary due to the pressure of the sheaf against fixed rods 32. As the next sheaf is carried up this process is repeated.

Said plates 31 are attached to the inner cone 30, as shown. They are curved at the front end, i. e. towards the base of the cone 30 so that as the stook is gripped by the stooking ring 1 and pulled out of the moulder 30, 31, 32, the sheaves will ride upon the top of the spacers and thus will not jam or wedge in between two spacers.

32 are outside cone rods, two in number. They will, of necessity, be very strong as they will have to hold six sheaves in place around the inside cone 30; they are in two segments or parts so that they can swing

open to allow the stook to be pulled out by the stooking ring 1.

Said hinged parts 32^a of cone rods 32 are so jointed that they can swing inward 5 towards the inner cone 30 to allow the sheaves to pass into the moulder 30, 31, 32, but will not swing outward apart from the segments to which they are attached. The opening of these outside cone rods 32, 32 must take place when the stook is gripped 10 by the stooking ring and pulled out of the moulder 30, 31, 32. Immediately on the stook being pulled out and clear of the moulder these rods 32, 32 must close firmly 15 and be ready to receive another load of sheaves. Said rods 32 open and close at the hinges 47, 47; they are carried by the coned hinge cleats 46 and held closed by the braces 48. As the stooking ring 1 comes forward 20 and grips the sheaves the outer ends of the braces 48 will be pushed forward. This will release the outer cone rods 32 and allow same to open.

33^a, 33^b are the sheaf carriers; these are 25 two in number and may be chains running on sprocket wheels. Each carrier is provided with fins 45 which project above the level of the rods of said sheaf holder 39, so as to catch the sheaves and carry them on 30 to the loader 42. Said carriers will run continuously while the machine is in action.

34 is a shelf of rods which direct the sheaves as they are thrown from the binding table of the binder onto the sheaf holder 39; 35 are several rods jointed at their top end so that they can swing away from the binder but can only come back to a vertical position where they meet a pin or the like. They are designed to allow the sheaves to be 40 thrown into the holder 39, but prevent any from falling back and obstructing the space marked "Z" along which the vertical pivot 13 and uprights 14 travel when the stooking ring 1 is grasping its load.

45 36 is a portcullis of rods. The function of these rods is to arrest any sheaf that is thrown from the binder while the vertical pivot 13 and uprights 14 are forward in the space "Z"; their downward and upward movement may be brought about by any 50 suitable known mechanism (not shown) on the forward and rearward travel respectively of uprights 14.

55 38, 38^a, 38^b is one of a pair of sheaf arresters. It consists of a normally vertical part 38^a an upwardly directed outer part 38^b and an intermediate depressed part 38. Said 60 arrester is pivotally supported at 38^c. They are designed to ensure that only one sheaf at a time may be on the loader 42. When said loader 42 is empty the vertical part 38^a falls under the influence of gravity, below the level of the rods of the sheaf holder 39. As a sheaf falls on the carrier 33 and is 65 carried on to the lower end of the loader 42

it depresses 38^b and raises 38^a. Now, no more sheaves may be carried on to the loader 42 (which has stopped while the sheaves are being grasped and pulled out of the moulder 30, 31, 32, by the stooking ring 1) 70 until the loader 42 starts running again.

The sheaves are thrown from the binder onto the sheaf-holder 39 at varying speeds according to the width of the swathe cut, the speed at which the binder is travelling, 75 and the thickness of the standing grain. The sheaves cannot be carried in a continuous stream into the moulder 30, 31, 32, as there must be a stop while the stook is being grasped by ring 1 and pulled out. Hence, 80 the provision of holder 39 to receive the two or three sheaves thrown out during such delay. Said sheaf holder 39 comprises, as shown, a vertical part to keep the sheaves from falling into the space "Z", a horizontal 85 part, and a sloping part—the latter directing the sheaves into the moulder 30, 31, 32.

Said wall 40 is a sheet of metal against which the sheaves abut whilst being thrown from the binder, and carried into and held 90 in the moulder 30, 31, 32.

Said fins 43 and 45 of the loader and carrier, respectively, may be made of loops of metal; as the sheaves come up against 38^a and meet strong resistance the fin 45 will 95 slip under the sheaf and allow the carriers 33 to continue running.

Referring now to Fig. 5 of the drawings, secured on the bar 3 is a plate piece 61 having an inclined upper surface 61^a and a 100 posterior vertical surface 61^b; and a flat blade of spring steel 67 hinged at 68.

Secured to the posterior part of the main frame is a rigid bar 65 the front edge whereof is inclined and on its upper surface there 105 is provided a projection 66.

Assuming the parts are in the position shown in Figs. 1 and 2 and the gliding frame 3, 13, 15, is advanced in the direction of the arrow, when the stooking closers 25, 25^a meet the stook of sheaves the ring components are closed (as shown in Fig. 3) to 110 grasp the stook.

As the bar 3 of the gliding frame moves forward, arm 4, which is a flat piece of 115 spring steel and secured to the adjacent pivot 13, by reason of its spring construction, rides up the inclined plane 61^a, and enters the space between the vertical portion 61^b and blade 67; thus ring 1 is locked 120 in a closed position.

The gliding frame is now released from suitable carrying mechanism in any convenient way.

As sheaves vary in length and must be 125 grasped at a suitable distance from the heads, appropriate means may be provided whereby the forward travel of the gliding frame is automatically adjusted to suit varying lengths of sheaves. 130

The cones 32 now open to allow the sheaves to be withdrawn, moves backward and re-engages with the gliding frame, and withdraws the sheaves from the cone 32; when 5 withdrawn the weight of sheaves causes the ring to turn to a horizontal position.

The stock now travels rearwardly of the machine and drops solidly on to the ground.

In the continued rearward or retractive 10 movement of the gliding frame 3, 13, 15 (which movement is equal to the forward movement of the whole machine) the lever 4 meets bar 65 which flexes blade 67 laterally out of the way of lever 4, but the projection 66 engages lever 4.

As soon as bar 65 has flexed blade 67 out of the way it passes under lever 4 and the extension 49 of bar 4 meets the interceptor 63 secured to the main frame with the result 15 that the ring 1 is opened somewhat.

Now the gliding frame having reached the posterior limit of its travel begins immediately to move forward, but lever 4 is for a time retarded through the engagement of 20 a catch portion 66 with it, the result being that the ring 1 is completely opened, swings away from the stock and moves backward at a speed equal to the forward movement of the machine.

25 In the continued forward movement of the gliding frame, lever 4 automatically disengages from projection 66, the extension 49 of lever 4 engages the anterior interceptor 62 of the main frame and ring 1 is swung forward. In the forward movement of lever 4 it rides over blade 67. Said interceptor 62 is of a spring form so shaped that extension 49 of lever 4 in the rearward movement 30 of the gliding frame will pass it.

35 40 What I claim is:—

1. A shock positioning apparatus adapted to accompany a binder and receive bunched sheaves and deposit said sheaves as a shock in an upright position on the ground, said apparatus including a main frame, tracks carried thereby, a gliding frame on some of said tracks, a shock carrying ring supported from said gliding frame, and means engaging other tracks to cause said ring to be 45 raised and lowered during a period of travel by said gliding frame.

50 55 2. A shock positioning apparatus as called for in claim 1, wherein said shock carrying ring is composed of opposed members adapted to swing to and from each other.

3. Means for manipulation of a shock, said means comprising a ring composed of separable members, pivotal means for said ring members permitting of said ring members

being swung from a vertical to a horizontal 60 plane, and means adapted to vertically and horizontally reciprocate said ring.

4. Shock manipulating means as called for in claim 3, wherein said pivotal means includes pillars, and the last mentioned means 65 includes a gliding frame supporting said pillars.

5. Shock manipulating means as called for in claim 3, wherein the last mentioned means includes tracks and a gliding frame, one of 70 said tracks causing vertical reciprocation of said ring.

6. Means for manipulating a shock, comprising a ring which when horizontal is adapted to receive a shock and when vertical discharge the shock, said ring being composed of members adapted to be opened and closed relative to the shock, said members being closed about the shock by contact therewith, and means adapted for opening 80 said ring members.

7. In a shock manipulating apparatus adapted to accompany a binder, a mould adapted to receive and place in shock formation a plurality of sheaves, and a ring like structure adapted to remove a formed shock from the mould and place it in an upright position on the ground. 85

8. A shock manipulating apparatus, as called for in claim 7, wherein said mould includes an inner rotary conical frame, and an outer conical frame, between which frames sheaves are placed in shock formation. 90

9. A shock manipulating apparatus, as called for in claim 7, and endless sheaf carriers adapted to load said mould. 95

10. A shock manipulating apparatus, as called for in claim 7, wherein said mould includes an inner rotary conical frame and an outer conical frame, between which frames sheaves are placed in shock formation, and a mould loader adapted to feed sheaves to said mould and rotate said inner conical frame. 100

11. In a shock manipulating apparatus, adapted to accompany a binder, a mould adapted to receive and place in shock formation a plurality of sheaves, a sheaf receiving receptacle adjacent said mould, a shock receiving receptacle adjacent said mould, means in said sheaf receiving receptacle adapted to load said mould, and means adapted to remove shocks from said shock receiving receptacle. 105

110 In testimony whereof I affix my signature.

LYLE JOHN CAMERON.
